UNITED STATES PATENT OFFICE

SIDNEY E. ANDERSON, OF BROOKLYN, NEW YORK, ASSIGNOR TO WESTERN ELECTRIC COMPANY, INCORPORATED, OF NEW YORK, N. Y., A CORPORATION OF NEW YORK

RECEIVING CIRCUIT

Application filed August 29, 1923. Serial No. 659,885.

The present invention relates to electric wave reception and amplification and more particularly to plural stage radio frequency amplification.

5 An object of the invention is to secure high amplification at radio frequencies in a circuit possessing constancy and stability of operation.

In a co-pending application of Herald T. Friis, Serial No. 640,810, filed May 28, 1923, a radio receiving circuit is disclosed having a tuned high frequency input circuit for a radio frequency amplifier, in which the grid and filament of the first stage are connected 15 across a portion of the inductance of the tuned circuit while the plate is provided with a connection through a small condenser to a point on the inductance on the side of the filament tap opposite from the grid. When 20 this condenser has a capacity of the same order of magnitude as the internal capacity of the tube, it is found that an adjustment may readily be obtained which will render the circuit stable as regards any tendency to 25 developed sustained oscillations or "sing- 30 ing."

Where several stages of radio frequency amplification are employed, there is found to be a tendency for individual stages to develop "singing" on account of the resonant 35 characteristics of the radio frequency transformers or other interstage circuits and the internal capacity of the amplification tubes. As is well known, this tendency to "sing" 40 limits the amount of amplification which can be obtained in any circuit so that the more effectively the "singing" tendency can be reduced, the greater can be the amplification, as well as the general stability and con- 45 stancy of operation of the circuit.

According to the invention, each stage of a plural stage amplifier circuit is balanced 50 against developing free oscillations or "sing- 55 ing" by means of a capacity external to the tube for opposing the action of the internal capacity in developing self-sustained oscillations.

In the drawings, Fig. 1 shows a typical 55 radio receiving circuit embodying, in one 60 form, the anti-singing feature of the inven- 65

tion; and Fig. 2 is a similar representation of a modified form of receiver.

Referring first to Fig. 1, an open antenna 1 is shown provided with the usual tuning 65 elements and having its inductance associated in energy-transfer relation with the inductance 3 of the secondary tuned circuit 2 which comprises also the adjustable condenser 4. The first stage radio frequency amplifier A₁ has its filament connected to an intermediate 70 point of the inductance and its grid connected to a terminal of the inductance. Connection is made from the plate of this amplifier to the second stage amplifier A₂ through the radio frequency transformer T₁. The 75 plate or anode of the amplifier A₁ also is connected through the condenser 5 to the terminal of the inductance 3 opposite to that connected to the grid. The purpose of this connection will be described hereinafter. 80

The plate or anode of the amplifier A₂ is connected by means of the radio frequency transformer T₂ to the detector D and this anode also is connected through the condenser 6 to the anode of amplifier A₁. The output 85 circuit of the detector D contains a receiver R of any suitable type. The filaments of the tubes are supplied with heating current from source 7 and the anodes with space current from the common source 8. 90

The circuit of Fig. 2 differs only slightly 95 from that of Fig. 1 and a brief description of the points of difference will suffice. For the sake of illustration a loop antenna 10, tuned by variable condenser 4, is shown connected 100 to the first stage amplifier A₁ in place of the open antenna of Fig. 1, although either type of antenna may be employed in connection with either figure. In the modification shown in Fig. 2, the condenser 6' corresponding to 105 condenser 6 of Fig. 1, is connected to the same loop terminal as condenser 5.

In operation, the constants of the antenna 11 and the tuned circuit 2 and the coupling 110 between them or the constants of the loop circuit if a loop is used, are adjusted to suit the wave length and other conditions of any given case. The received radio frequency waves impressed across the grid and filament 115 of the amplifier A₁ are amplified in this tube 120

and transmitted through the radio frequency transformer T_1 to the input side of the amplifier A_2 where they are further amplified and transmitted through radio frequency transformer T_2 to the detector. The detector 5 operates in the usual manner to derive from the received waves the speech, music or other waves by which the radio wave is modulated at the transmitter.

10 On account of the unavoidable capacity which exists between the grid and plate elements of the vacuum tubes, there is a certain amount of energy directly transferred across the space between the grid and plate, 15 these elements acting as a condenser. This capacity, therefore, affords a coupling between the grid and plate circuits and at the same time cooperates with the inductance elements of these circuits to give the circuits 20 a natural period. Due to the amplifying action of the tube, together with the tuning and feedback coupling afforded by the tube capacity, each tube acts or tends to act as a generator of oscillations provided the amplification factor is sufficiently large.

As explained in Friis' application, supra, the condenser 5 also affords a coupling between the plate and grid circuit of the amplifier A_1 and due to its connection to the opposite terminal of inductance 3 from that connected to the grid, the potential variations transmitted through the condenser 5 to the grid circuit are of such phase as to oppose the potential variations transmitted back to 30 the grid circuit through the grid-to-plate capacity. Condenser 5 therefore opposes the setting up of sustained oscillations in the tube circuit.

Condenser 6 of Fig. 1 or condenser 6' of Fig. 40 2 acts in a somewhat similar manner to prevent the building up of sustained oscillations in the circuit of the amplifier A_2 or in the general amplifier circuit.

By reason of the fact that transformers are 45 used to couple the amplifier tubes, a phase shift is introduced between the stages. The exact magnitude of this phase shift depends upon the relative distribution of the various constants of the transformers.

50 It has been found in a radio frequency amplifier circuit employing transformers for coupling the tubes, that the amplifying factor has two maxima occurring at two distinct frequency values. The amplification maximum which occurs at the lower of the two frequencies appears to be due primarily to the parallel resonance of the inductance of the secondary winding with its effective distributed capacity and the effective input capacity of the following tube. The amplification maximum occurring at the higher frequency is due primarily to the series resonance of the leakage inductance of the transformer with the same capacity mentioned 55 above. The relative phase of the plate and

grid circuit E. M. F.'s. will obviously not be the same at these two resonance frequencies. In practice, it has been found that regardless of the direction of winding of the transformers T_1 and T_2 , a tendency of the circuit 70 to sing at one of these two resonance points will be more effectively opposed by the circuit of Fig. 1 while with the same circuit arrangements the circuit of Fig. 2 will be more effective to prevent singing at the other 75 of the two resonance points. In some cases a combination of the arrangement of the balancing condensers as shown in Fig. 1 with the arrangement shown in Fig. 2 may be employed, for example, one of the two condenser 80 arrangements may be used for certain stages and the other arrangement for other stages. In general an arrangement of the balancing condensers and an adjustment of their magnitudes may readily be determined which will 85 effectively oppose the production of oscillations in all of the stages. On account of the lack of complete data as to the characteristics of radio frequency transformers it will ordinarily be impossible to predict without an 90 exact measurement of the amplification characteristics of each portion of the circuit the exact arrangement which will give the greatest freedom from oscillation, and persons skilled in the art will generally prefer to determine the best arrangement by experiment. 95

Any number of radio frequency amplifiers may be connected in tandem and a condenser corresponding to condenser 6 or 6' may be 100 employed for each stage.

The circuits that have been described are to be taken as merely illustrative of particular embodiments of the invention but are not to be construed as limiting the invention, 105 the scope of which is defined in the claims.

What is claimed is:

1. In a receiving circuit a tuned input circuit, a vacuum tube amplifier having filament, grid or impedance control and plate electrodes, the filament and grid being connected to different points of the inductance of said tuned circuit, a condenser of the order of magnitude of the inherent capacity between said grid and plate connected between the plate electrode and a point in the inductance on the opposite side of said filament connection from the point to which the grid is connected, a second vacuum tube, a transformer having its primary winding connected between the plate and cathode of the first tube and its secondary between the grid and cathode of the second tube, and a condenser connecting said two plates and having a capacity of the order of magnitude of the inherent capacity between the grid and plate of said second tube. 115

2. In a wave repeating circuit, a plurality of vacuum tube repeaters connected in tandem, each tube having a cathode, an anode, 120

and a grid or control element, means including an adjustably tuned circuit for impressing on said repeating circuit the waves to be repeated, connections from the cathode and grid of the first tube to points on the inductance of said tuned circuit, a condenser connected between the anode of the first tube and a point on said inductance on the opposite side of the point of connection of the cathode from that to which the grid is connected, a transformer having its primary winding connected between the anode and cathode of the first tube and its secondary connected between the grid and cathode of the second tube, and a condenser connected between the anode of said second tube and the anode of the first tube, said condenser connected between the anodes of the two tubes having a capacity of the order of magnitude of the inherent capacity between the grid and plate of said second tube.

In witness whereof, I hereunto subscribe my name this 24 day of August, A. D., 1923.

SIDNEY E. ANDERSON.
